UNITED STATES PATENT OFFICE.

REUBEN W. FOSTER, OF MANKATO, MINNESOTA.

OVEN.

1,262,659.

Specification of Letters Patent. Patented Apr. 16, 1918.

Application filed September 2, 1916. Serial No. 118,244.

To all whom it may concern:

Be it known that I, REUBEN W. FOSTER, a citizen of the United States, residing at Mankato, in the county of Blue Earth and State of Minnesota, have invented certain new and useful Improvements in Ovens, of which the following is a specification.

My invention relates to improvements in the ovens of stoves and ranges, its object being to provide improved means for the drawing out of one or both grates in the opening of the door.

Referring to the drawings,

Figure 1 is a section taken just inside one side wall of the oven with both grates withdrawn.

Fig. 2 is a similar view with the door closed.

Fig. 3 is a detail of a locking lever forming part of my invention.

Fig. 4 is a detail of a supporting bracket for one end of an actuating bar for the locking levers, and

Fig. 5 is a vertical cross section of the oven taken inside the door.

Referring to the drawings A represents an oven, inside the side wall of which are supported rails 2 upon which the upper and lower grates 3 and 4 slide. The rails 2 as shown, are held spaced from the side walls of the oven as by supporting brackets 5. The lower grate is formed with integral upwardly extending side walls 6 each wall at its upper edge supporting a socket plate 7 with which socket plates the downwardly projecting ends 8 of the lever arms 9 are adapted to interlock. Each of the lever arms 9 have fulcrum support 10 under the upper grate, the outer ends of the lever arms 9 extending slidably through the slotted brackets 11. For the purpose of depressing the overlapping inner ends of the lever arms 9 to carry the outer ends of said arms out of interlocking engagement with the lower grate I provide a bar 12. The bar 12 is slidably supported underneath the upper grate by means of a bracket 13 secured under the front end of the grate and by a pin 14 projecting downwardly from the 50 grate through a slotted opening 15 in the bar 12, the head of the pin acting as a support for the under side of the bar. The front end 16 of the bar extends downwardly to form a finger hold and the rear end 17 of the bar extends downwardly and rearwardly to form an actuating cam for

the inner ends of the lever arms 9. When the bar 12 is forced rearwardly, as shown in Figs. 1 and 2, the downwardly projecting rear end 17 extends beyond the inner ends of the lever arms 9, allowing said lever arms to swing freely upon their fulcrums 10, thus causing the heavier outer ends of the arms 9 to drop by gravity into locking engagement with the socket plates 7. By pulling the bar 12 forwardly, the downwardly projecting rear end 17 of the bar is brought into actuating engagement with the inner ends of the lever arms 9 to force said ends downwardly and lift the outer ends 8 out of locking engagement with the socket plate 7. This leaves the upper and lower grates unconnected so that the lower grate may be drawn outwardly without the upper grate being moved.

For the purpose of pulling the lower grate outwardly as the oven door B is opened, I provide the following described mechanism.

Lever arms 18 have fulcrum support 19 on the opposite side walls of the oven below the lower grate, said lever arms extending upwardly between the side walls of the oven and the side walls of the lower grate. Anti-friction rollers 20 are journaled upon the upper ends of the lever arms 18 and project inwardly into upwardly and forwardly curved slots 21 in the upwardly projecting side walls of the lower grate. A link 22, shown in dotted lines, intermediately connects each lever arm 18 with a cam lever 23 at a point above the pivotal support 24 of the cam lever. The upper end of each cam lever is pivotally connected by a link 25 with a suitable bracket 26 extending inwardly from the oven door. The links 25 are preferably detachably connected with the brackets 26 as by having outer ends of the links formed with slots 27 to receive the brackets 26, whereby to allow the above described mechanism to be disconnected from the door and permit the door being opened and closed without moving the grates. The platform portion 28 of the lower grate is preferably removably supported upon the side bars of the grate so as to allow it to be removed to leave the center of the oven unobstructed in case it is desired to place things upon the oven bottom.

As will be evident by referring to Figs. 1 and 2 the opening of the oven door will, through the medium of the links 25, turn

the cam levers 23 forwardly upon their pivotal supports, motion being transmitted through the links 22 to the levers 18 to pull the bottom grate forwardly by reason of the pressure of the anti-friction rollers 20 against the front edges of the slotted openings 21 in the side walls of the lower grate. Similarly the closing of the oven door will push the lower grate back into the oven, the anti-friction rollers traveling upwardly in the slots 21 as the lower grate is pulled outwardly and downwardly in the slots 21 as the lower grate is pushed back. Where the upper grate is locked to the lower grate by the lever arms 9, the two grates will be pulled out together, or the lower grate may be pulled out independently of the upper grate by disconnecting the upper and lower grates as pointed out.

Should it be desired to open the door without operating the shelves, this may be accomplished by opening the door and unhooking the links 25 from the brackets 26.

I claim:

1. In combination with an oven and the door thereof, a pair of grates slidably supported within said oven, a connection between one of said grates and said door causing said grate to be pulled out as the said door is opened, and means carried by the other grate normally interlocking with said first mentioned grate, and said means being

separable to allow said grates to be disconnected and said connection between the door and one grate being separable to allow said door to be disconnected therefrom and permit the door being opened without affecting either grate.

2. In combination with an oven and the door thereof, a pair of grates slidably supported within said oven, a connection between one of said grates and said door causing said grate to be pulled out as said door is opened, means carried by the other grate normally interlocking with said first mentioned grate, and means holding said locking mechanism withdrawn to maintain said grates in unconnected position.

3. In combination with an oven and the door thereof, a pair of grates slidably supported within said oven, lever connections between one of said grates and said door whereby said grate is pulled out as said door is opened, lever arms carried by the other grate and normally interlocking with said first mentioned grate, and slidable means actuatable to move said lever arms out of locking position.

In testimony whereof I affix my signature in presence of two witnesses.

REUBEN W. FOSTER.
